HAME

John M. Glaser, Buffalo, N. Y., assignor to U. S.
Hame Company, Buffalo, N. Y.

Application July 19, 1934, Serial No. 736,015

7 Claims. (Cl. 54—25)

This invention relates to hames and more particularly to hames of the type constructed partly of wood or other non-metallic material, and partly of metal.

The objects of this invention are to produce a hame of this type of greater strength and lighter weight than similar hames heretofore constructed; also to provide a hame of this kind which can be more readily constructed and which is more durable than similar hames heretofore made; also to provide a hame having a non-metallic body portion which is mortised to receive a portion of the metal reinforcing strip to provide a better cooperation between the parts; also to provide a hame in which the body portion is reinforced by means of a metal strip of channel-shaped cross section; also to provide a hame of this kind in which the channel shaped reinforcing strip and the body portion of the hame are provided with cooperating portions for holding these parts in their correct operative positions relatively to each other; also to improve the construction of hames in other respects hereinafter specified.

In the accompanying drawing:

Fig. 1 is a front view of a hame embodying this invention.

Fig. 2 is a side view thereof.

Fig. 3 is a fragmentary enlarged front view of the lower end of the hame.

Fig. 4 is a similar fragmentary view of the upper end of the hame.

Figs. 5 and 6 are sections thereof taken on lines 5—5 and 6—6, Fig. 4.

Fig. 7 is a section thereof, on line 7—7, Fig. 1. A represents the body portion of the hame which is usually made of wood, but which may be made of any other material. In hames of this kind a flat metal strip or back iron is usually employed for reinforcing the outer edge of the hame, and is secured thereto at intervals by rivets or bolts. In accordance with this invention, I provide the hame with a reinforcing strip of such cross sectional shape that a portion of the strip may enter into a mortise in the body. The mortise in the body portion and the part of the reinforcing strip extending into the same preferably extend throughout the greater portion of the length of the hame, so that a uniform reinforcement of the hame substantially throughout its length will result, instead of having the strip reinforce the hame body against certain stresses only at the rivets or bolts connecting the body and strip. The reinforcing strip may

of cooperating with a longitudinal groove or mortise in the body. In the construction illustrated, a reinforcing strip B of channel-shaped cross section is employed and is arranged with the flanges b of the channel extending toward 5 and engaging with the body portion A of the hame.

In order to provide for the desired cooperation between the body of the hame and the reinforcing strip, the hame body is provided at the two 10 opposite edge portions thereof with mortises 9 cut in the wooden or non-metallic body portion and into which the flanges b of the channel may enter. Preferably a snug fit is provided between the legs of the channel member B and the mortised portion of the body A, so that lateral movement of the reinforcing strip B with reference to the body of the hame is prevented, and so that any flexing or bending of the hame body, due to the strains to which it may be subjected, 15 will be transmitted to the reinforcing strip B. By means of this arrangement, an excessive increase in the width of the hame because of the depth of the channel-shaped reinforcing strip B is also prevented.

Since a reinforcing strip of channel or other structural shape has materially greater strength than a flat or curved strip of the same cross sectional area, it is possible to make my improved reinforcing strip of relatively thin metal and yet 20 produce a hame of greater strength than those heretofore made in which reinforcing strips of rectangular cross section were used. It is also possible to dispense with some of the rivets which were heretofore necessary to hold a flat reinforcing strip in place on the hame body, and consequently, I employ ordinary nails 10 at intervals for holding the reinforcing strip on the body portion of the hame. Such nails do not weaken the body portion to the same extent as rivets, 25 for the reason that the nails do not extend entirely through the body portion and may be of smaller diameter than rivets heretofore used. This results in a further increase in the strength 30 of the hame.

In certain types of hames, it is desirable to have the reinforcing strip overlap the ends of the hame. I can accomplish this result by means of my improved reinforcing strip by either removing from the ends of the strip any legs or 35 flanges, so that the ends of the strip will be substantially flat, or by flattening these ends by folding such legs or flanges against the web of the reinforcing strip. For example, when a channel-shaped reinforcing strip is employed, I 40

can bend or fold the flanges **b** toward each other and against the web of the channel. These folded legs or flanges **11** consequently substantially double the thickness of the flat portion of the reinforcing strip and produce additional strength at the ends of the hame. These flattened portions of the reinforcing strip can be bent over the opposite ends of the hame, as indicated at **14** and **15**, and may be secured in their correct positions by means of rivets **16** and **17** passing through the bent-over portions **14** and **15**, the body of the hame, and the channel-shaped portion of the reinforcing strip **B**, as clearly shown in Figs. 1, 3, 4 and 5. To the lower bent-over portion **15** of the hame, the usual hame loop **18** may be applied. These bent over portions enable the reinforcing member to be securely held against movement lengthwise of the hame body. When this construction is used, it is also possible to eliminate the nails **10** entirely, since the reinforcing strip will be securely held against endwise as well as lateral movement relatively to the body. When the legs or flanges are bent inwardly at the ends of the reinforcing strip **B**, they also act as wear strips or members for the hame loop **18**.

20 represents the usual hame ring which may be passed through the eye of an eye bolt **21** extending through the hame and riveted over at its end on the opposite edge of the hame. **22** represents the usual trace connection which may also be of any suitable or usual construction, and to which a hame or trace hook **23** may be connected at different elevations. The trace connector may also provide for the securing of a breast strap ring **24** to the hame.

An end of the body portion of the hame, for example, the upper end, as shown at **14**, is preferably formed flat and extends at nearly a right angle to the opposite sides of the hame, and the adjacent end portion of the reinforcing strip is bent over this flat end of the body portion, so that a very much stronger structure results than when the upper end of the body portion is rounded. When the hame is formed in this manner and subjected to severe strains, the flattened end of the body portion bears against a flat face of the reinforcing strip which prevents relative displacement of the strip and body portion, and also provides two flat surfaces of fairly extensive area which bear one against the other and thus resist to a greater extent any relative displacement of the reinforcing strip and body.

Hames of the kind herein described are lighter and have greater strength than hames of this type heretofore made, and this is, of course, of material advantage, since it relieves the draft animal of a corresponding amount of weight without sacrificing the strength of hame.

60 I claim as my invention:

1. A hame having a non-metallic body provided with a mortise extending lengthwise thereof, a reinforcing strip secured to a side of the hame body and having a flange extending into said mortise, and a web extending parallel to said

side, said flange being folded flatly against said web at an end of said hame and the end portion of said strip with said folded flange being bent across the end of said body portion.

2. A hame having a non-metallic body provided with a mortise extending lengthwise thereof, a reinforcing strip secured to a side of the hame body and having a flange extending into said mortise, and a web extending substantially parallel to said side, said flange being folded flatly against said web at the ends of said strip, said ends of the strip being bent across the ends of said hame body to hold said strip against movement lengthwise of said hame body.

3. A hame having a non-metallic body portion, and a reinforcing strip of metal secured to the outer edge thereof and of channel-shaped cross section, and having the flanges of the channel at an end thereof folded inwardly, said end being bent over and secured to the end of the body portion.

4. A hame having a non-metallic body portion provided with mortises extending lengthwise thereof at the edges of one side of said body portion, a metallic reinforcing strip secured to said side of the body portion and of channel-shaped cross-section and having the flanges of the channel extending into said mortises for holding said strip against movement laterally of the legs of the body portion, said strip having the flanges at the ends thereof folded inwardly against the web of the channel, said ends of the strip being bent over the ends of the body portion to hold said strip on said body portion and against movement lengthwise thereof.

5. A hame having a non-metallic body portion, a reinforcing strip of channel-shaped cross section secured to one side of said body portion and having the flanges of the channel at the ends of said strip folded against the web of the channel, said end portions of the strip being bent over the ends of the body portion.

6. A hame having a non-metallic body, a reinforcing strip of metal secured to a side of the hame body, and having a web extending substantially parallel to said side and a flange extending substantially perpendicular to said web and engaging said body, said flange being folded flatly against said web at an end of said hame, and the end portion of said strip with said folded flange being bent across the end of said body portion.

7. A hame having a non-metallic body portion and having a reinforcing strip of metal secured to the outer side of said hame, said reinforcing strip having a web extending substantially parallel to said side of the hame and a flange extending substantially perpendicular to said web and engaging said body, said body portion having a flat end extending at an angle to the side to which said reinforcing strip is secured, and the end of said reinforcing strip being bent around said angle to lie flatly against said flat end of said body portion.

JOHN M. GLASER. 65
